UNITED STATES PATENT OFFICE.

SAMUEL F. ARBUCKLE, OF CONNERSVILLE, INDIANA, ASSIGNOR TO UNITED STATES AUTOMOTIVE CORPORATION, OF CONNERSVILLE, INDIANA.

ТИЛТИНГ РЕФЛЕКТОР ДЛЯ ЛАМП.

1,424,793.

Specification of Letters Patent. Patented Aug. 8, 1922.

Application filed March 18, 1921. Serial No. 453,516.

To all whom it may concern:

Be it known that I, SAMUEL F. ARBUCKLE, a citizen of the United States, and a resident of Connerville, county of Fayette, and 5 State of Indiana, have invented a certain new and useful Tilting Reflector for Lamps; and I do hereby declare that the following is a full, clear, and exact description thereof, reference being had to the accompanying 10 drawings, in which like numerals refer to like parts.

This invention relates to a tilting reflector construction particularly adapted to small and cheaply constructed automobile 15 lamps, whereby the reflector may be operated from the dash to tilt it so as to direct the light straight forward substantially parallel with the road and to permit it to return to normal position for directing the 20 light downwardly at an angle to prevent the glare from blinding the passerby.

The particular feature of this invention lies in the construction and manner of mounting the reflector in the lamp casing, 25 and the mechanism operable from the dash for actuating the reflector, whereby dust will be prevented from seeping into the casing through which the operating device passes, or around the reflector or reflector 30 ring.

Another feature of the invention is the arrangement of the manually controlled actuating mechanism whereby the reflectors will be positively and completely actuated 35 regardless of the position or torsion of the frame, and the variation in the rods or cables is compensated for. This construction will also permit the adjustment of the lamps without affecting the relative position 40 of the reflector to the casing.

Still another feature relates to the mounting of the reflector to prevent rattling from any vibration that may be set up in the lamp, which is accomplished by the use of 45 two supports at the top where there is the greatest vibration, and a positive connection with the actuating mechanism at the bottom.

The full nature of this invention will be 50 understood from the accompanying drawings and the following description and claims.

In the drawings Fig. 1 is a central vertical cross section through a lamp showing the 55 reflector in normal position. Fig. 2 is a

front elevation of the lamp with the edge portion of a portion of the closure removed. Fig. 3 is a section taken on the line 3-3 of Fig. 2. Fig. 4 is a section taken on the line 4-4 of Fig. 1. Fig. 5 is a plan view of the 60 reflector control from the dash. Fig. 6 is a section taken on the line 6-6 of Fig. 5.

In the drawings there is shown a lamp having a casing 10 provided with an annular bead 11 and laterally extending flange 65 portion 12. Mounted in the casing there is a reflector containing ring 13 secured therein in any suitable manner, as shown herein by the wire retaining ring 14. Said ring 13 is provided with the usual annular groove in 70 which is mounted a sealing guard 15 against which the lens 16 abuts and is securely held in position by the lens rim or lens closure 17. The closure 17 is provided with inwardly extending lens engaging fingers 18 75 which hold the lens in position and is provided with an outer flange portion adapted to telescope over the casing flange 12 and be secured in position thereon by the inwardly and radially extending pins 19 extending 80 through suitable slots in said flange in the usual manner. The construction above described is that commonly employed on lamps of this character or may be changed to any other construction if so desired without affecting this invention.

For pivotally supporting the reflector in said casing, there is a hinge spring 20 shown in Fig. 3 secured in any suitable manner to the reflector containing ring 13, as shown 90 herein by the rivets 21. As shown in Fig. 2 there are two pivot points, one on each side of the center of the lamp toward the top thereof wherein the hinge spring is mounted. Said spring is arranged to encircle the 95 rearwardly extending flange portion of the reflector containing ring and engage and hold against said flange portion the inwardly turned edge 22 of the reflector 23, whereby said reflector will be suspended by 100 said ring so as to swing therefrom in a vertical plane. The spring tension of the hinge spring 20 yieldingly secures the top of the reflector at its hinge points against a depressed portion 24 of the ring 13. The relative diameters of the reflector and the ring 13 are such that the reflector is permitted to move freely therein and is spaced slightly away from said ring, as shown in Fig. 1.

Mounted in the reflector there is the usual 110

rearwardly extending sleeve 25 in which is slidably mounted a bayonet slotted lamp socket 26 adapted to hold the lamp 27. The socket is connected in the usual manner by 5 the plug 28 and wires 29 to the plug 30 for the desired electrical connection. For focusing the lamp 27 in the reflector there is provided an ear 31 projecting from the socket 26 through a slot in the sleeve 25 through 10 which the screw 32, which is mounted in an ear 33 formed on said sleeve, is adapted to screw for sliding the socket forwardly and rearwardly in said sleeve. At the rear of the casing there is an opening plugged by 15 the screw bolt 34 for permitting access to the screw 32 for focusing said lamp.

For actuating said reflector there is a U-shaped member 35 fixedly secured at each end to the lower edge of the reflector, as 20 shown in Fig. 4. The rear portion of said member is bent inwardly to provide a seat for the actuating lever 36 and is yieldingly connected to the rear of the casing by the spiral springs 37 secured at one end to 25 said member and at the other end to the hook 38 riveted to said casing. This arrangement causes the reflector normally to be drawn back, as shown in Fig. 1, for directing the rays of light downwardly. The 30 actuating lever 36 extends through a suitable slot in the lower portion of the casing and is fulcrumed to a downwardly extending ear 36^a thereon at the point 39. It is provided with a recess or any suitable 35 means for engaging the member 35 at its upper end and is pivotally secured to a cable or rod 40 at its lower end. On each side of said lever there are downwardly 40 projecting ears 41 and 42 mounted on the lower side of the casing arranged to limit the pivotal movement of said lever and permit the adjustment of said movement by means of the stop screws 43 and 44 extending therethrough in position to be engaged 45 by said lever and limiting the movement thereof. For preventing dust from entering through the opening in the lower portion of said casing there is provided a flexible dust 50 guard 45, such as cloth, which may be cemented to the inner surface and surround the lever 36. Upon pulling back on the cable or rod 40 the lever will force the reflector forwardly into position to direct the rays substantially parallel with the rod, 55 and upon releasing the rod 40 the springs 37 will return the reflector to the normal position shown in Fig. 1. The cable 40 may extend rearwardly through the support 46 from each lamp, as shown in Fig. 5, and 60 pass to suitable pulleys 47 mounted near the dash 48 of the vehicle, thence around the pulleys 49 and up to a pulley 50 having its hub extending through the dash and mounted on a lever 51. The lever 51 is pivoted 65 at 52 on the dash and is provided with a

handle 53, whereby upon moving the handle down the pulley 50 will be raised so as to draw the cable rearwardly and force the reflector to vertical position. For retaining the reflector in vertical position, any suitable arrangement may be used for securing the lever 51 in that position such as friction or pin locking means engaging suitable holes in the dash board. By means of this or a similar arrangement of the cable, the reflectors will be operated by an equal force, the pulley 50 equalizing the cables through the springs 54.

The reflector may be readily installed in the casing by hooking the spring 37 on the hook 38, seating the member 35 in position with respect to the lever 38 and then using a tool to depress the hinge spring 20 to permit the upper portion of the reflector to be hooked over the end thereof.

The invention claimed is:

1. In combination with a lamp casing and closure therefor, of a tilting reflector device including a reflector pivotally mounted in said casing, an actuating lever extending through said casing and pivoted thereto, means for limiting the movement of said lever, a spring mounted between said casing and reflector having its respective ends secured thereto for yieldingly maintaining said reflector in normal position, a member secured to said reflector in position to be engaged by said lever, and means secured to the lower end of said lever for operating the same for causing it to engage said member and move the reflector to tilted position against the action of said yielding means.

2. In combination with a lamp casing and closure therefor, of a tilting reflector device mounted in said casing, means for pivotally mounting said reflector in said casing, an actuating lever extending through said casing, a member secured to the lower portion of said reflector adapted to be engaged by one end of said lever, means for yieldingly holding said reflector in normal position, means for operating said actuating lever, and means for limiting the movement thereof.

3. In combination with a lamp casing and closure therefor, of a tilting reflector device mounted in said casing, means for pivotally mounting said reflector in said casing, an actuating lever extending through said casing, a member secured to the lower portion of said reflector adapted to be engaged by one end of said lever, a spring secured to said member and to the rear of said casing for yieldingly holding said reflector in downwardly tilted position, means for operating said actuating lever and adjustable stops mounted substantially at right angles to said casing for limiting the movement of said lever.

4. In combination with a lamp casing and closure therefor, of a tilting reflector device

- mounted in said casing, means for pivotally mounting said reflector in said casing, an actuating lever extending through said casing, a member secured to the lower 5 edge of said reflector in position to be engaged by said lever for moving said reflector to vertical position, a spiral spring having one end secured to said member and the other removably secured to the rear of said 10 casing for yieldingly drawing said reflector into downwardly tilting position, downwardly projecting ears secured to the lower portion of said casing on each side of said lever, and adjustable screws extending there- 15 through for limiting the movement thereof.
5. In combination with a lamp casing and closure therefor, of a tilting reflector device mounted in said casing, means for pivotally mounting said reflector in said casing, a 20 downwardly projecting ear cut in the lower portion of said casing, an actuating lever extending therethrough and pivoted to said ear, adjustable means for limiting the movement of said lever, a member yieldingly se- 25 cured to said casing and rigidly secured to
- said reflector adapted to be engaged by said lever for actuating said reflector and means secured to the lower end of said lever for operating the same.
6. In combination with a lamp casing and 30 closure therefor, of a tilting reflector device mounted in said casing, means for pivotally mounting said reflector in said casing, a downwardly projecting ear cut in the lower portion of said casing, an actuating lever ex- 35 tends therethrough and pivoted to said ear, rearwardly extending means for actu- ating said lever, a U-shaped member rigidly secured to the lower edge of said deflector, a coil spring having one end secured to said 40 member, and the other hooked to the rear of said casing, downwardly extending ears se- 45 cured to the under side of said casing on each side of said lever, and adjustable stop screws extending through said ears in posi- tion to be engaged and limit the movement of said lever.

In witness whereof, I have hereunto affixed my signature.

SAMUEL F. ARBUCKLE.
